(57) **CLAIM**

The ornamental design for a device battery charger, as shown and described.

DESCRIPTION

FIG. 1 is an isometric view of a bottom, back, and left side of the device battery charger;

FIG. 2 is an isometric view of a top, front, and left side of the device battery charger of FIG. 1;

FIG. 3 is a top plan view of the device battery charger of FIG. 1;

FIG. 4 is a bottom plan view of the device battery charger of FIG. 1;

FIG. 5 is a right side elevational view of the device battery charger of FIG. 1;

FIG. 6 is a left side elevational view of the device battery charger of FIG. 1;

FIG. 7 is a front elevational view of the device battery charger of FIG. 1; and,

FIG. 8 is a rear elevational view of the device battery charger of FIG. 1.

The broken lines are for the purpose of illustrating environmental structure and form no part of the claimed design.
